UNITED STATES PATENT OFFICE.

OSCAR N. AMUNDSON, OF HURLEY, WISCONSIN.

DEVICE FOR USE IN THE MANUFACTURE OF CONFECTIONERY.

Application filed December 6, 1923. Serial No. 678,999.

To all whom it may concern:

Be it known that I, OSCAR N. AMUNDSON, a citizen of the United States, residing at Hurley, in the county of Iron and State of Wisconsin, have invented certain new and useful Improvements in a Device for Use in the Manufacture of Confectionery, of which the following is a specification.

This invention relates to improvements in means for handling articles, such as confectionery, in order to expeditiously perform an operation thereon, such as coating.

A further object of this invention is the provision of a relatively simple and compact device adapted for use in the handling of articles, such as ice cream blocks and the like, whereby they may be engaged by the improved device, and separated ready to have an operation performed thereon, such as the dipping of the same in a confection for the purpose of coating the same.

A further object of this invention is the provision of an improved device to facilitate the handling, dipping, and coating of confectionery, being of such a nature that the same may be manually controlled during the handling of the confectionery to perform the dipping and coating of a relatively great number of pieces of confectionery or the like.

Other objects and advantages of this invention will be apparent during the course of the following detailed description.

In the accompanying drawings, forming a part of this specification, and wherein similar reference characters designate corresponding parts throughout the several views.

Figure 1 is a plan view of the improved device, showing the same in a collapsed position for engaging a series of articles, such as blocks of ice cream.

Fig. 2 is a plan view of the improved device, showing the same in an expanded relation with the articles of confection supported thereby in a separated relation and positioned as they will appear during the confection dipping or coating operation.

Fig. 3 is an edge elevation of the improved device.

Fig. 4 is an opposite edge elevation of the improved device, and

Fig. 5 is a cross sectional view taken substantially on the line 5—5 of Figure 2.

In the drawings, wherein for the purpose of illustration is shown but the preferred

embodiment of the invention the letter A may generally designate the improved article handling device, which may consist of a plurality of sections B pivotally connected by hinges C. Springs D normally tend to move the sections B away from each other; the action of the springs D being resisted by a chain E or analogous construction which limits the expanded amplitude of movement of the sections B.

Each of the sections B preferably includes a body portion 10, which is substantially rectangular in formation, and preferably made of wood. Sockets 12 are preferably formed in opposite side surfaces of each body portion 10, and in aligning relation, for receiving the springs D therein. A prong or hook member 15 is provided as a part of each section B, including the straight portion 16 which at one end thereof is inturned, as at 17, for seating within a suitable recess provided therefor in the top surface 18 of the body portion 10. The top surface of the body portion 10 is longitudinally grooved for receiving the rear end of the prong or hook 15, and at the front of the body portion 10 a retaining angle 20 is positioned, which includes a flange 21 lying over the top of the block or body portion 10 and secured thereto as by screws 22; and a forward flange 23 secured over the front surface 24 of the body portion 10, as by screws 25. The top flange 21 overlies the portion 16 of the hook 15 which overlies the top surface of the body portion 10; the angle 20 being provided with an aperture therethrough at the juncture of the flange portions 21 and 23 thereof, thru which the straight portion 16 of the hook 15 extends. The portion 16 extends for a considerable distance forwardly of the front surface 24 of the body portion 10, and at the free end thereof is downturned, as at 27, to provide a pointed shank at right angles to the portion 16, which is adapted for insertion in one of the articles of confection to be supported by the section B. The prong or hook 15 incident to the retaining angle 20 and the end 17 which fits within the body portion 10 is securely retained in a fixed position upon the latter.

The sections B are hingedly connected together on the rear surfaces of the body portion 10; the hinges C being provided for pivotally connecting adjacent sections B together, so that the axis of the hinge C for

adjacent blocks B is disposed in the plane of division on said blocks 10 when they are in abutting relation, and as is illustrated in Figure 1 of the drawings.

5 The springs D are provided for normally urging the sections B apart, and a spring D is provided for the adjacent aligning sockets 12 of adjacent sections B; it being of the compression type and acting to normally 10 urge the blocks B apart, as is clearly illustrated in Figure 2 of the drawings.

To limit the amplitude of expanded movement of the sections B, the chain E is provided, which includes a plurality of links 15 27. The extreme end links 27 are connected by nails, screws, or like securing elements 28 at the outer sides of the end sections B, and the intermediate portion of the chain E is placed about the forward surfaces of 20 the blocks or body portions 10 of the sections B, and is secured to each front surface of the blocks 10, by means of a screw 30 or the like. The links between the screws 30 of adjacent blocks permit a limited movement 25 of the sections B away from each other; this movement of the adjacent sections away from each other being the same for all of the sections of the device A, and as is illustrated in Figure 2 of the drawings, wherein the 30 maximum movement of the sections B away from each other is depicted.

The improved device A is primarily adapted for use in the handling and coating of ice cream blocks. The confection or ice 35 cream is cut into blocks G, substantially as is illustrated in Figure 1 of the drawings, and of course they are disposed in adjacent abutting relation immediately after the slicing operation thereon. In order to entirely 40 coat the same it is necessary to separate them. Manually separating each block G and coating it takes considerable time. To facilitate and expedite the operation the device A is manually collapsed into the position 45 illustrated in Figure 1, and in which position the body portion 10 of the sections B are in adjacent abutting relation with the springs D compressed therebetween and with the prongs or hooks 15 in parallel relation. 50 The spacing of the prongs 15 in such relation permits the shank portions 27^a to be inserted into all of the blocks of confection G. The device A is then suspended and the operator releases his clamping grasp thereon 55 so that the springs D are permitted to act in forcing the sections B apart into their maximum spaced relation as permitted by the chain E. The blocks of confection G will then be suspended in the relation substantially as is illustrated in Figure 2 of the drawings, and it can readily be understood that they are entirely separated and may be dipped into a coating substance, such as hot chocolate. After the dipping operation the 60 device A may be suspended in any approved 65

manner until the coating upon the blocks G has dried.

From the foregoing description of this invention it is apparent that a device for use in the manufacture of confection has 70 been provided which is relatively simple and compact in nature, and which may be manually operated to quickly and conveniently handle and coat confections.

Various changes in the shape, size, and 75 arrangement of parts may be made to the form of the invention herein shown and described, without departing from the spirit of the invention or the scope of the claims.

I claim:

1. A device of the class described comprising a plurality of article supporting sections, and means for relatively moving said sections away from or toward each other, whereby said sections when together may 85 engage and support a plurality of articles and when moved away from each other will separate said articles.

2. As an article of manufacture a confection handling device consisting of article 90 supporting sections, means for supporting the sections for relative movement, and means normally urging the sections away from each other.

3. A device for use in the manufacturing 95 of confections comprising a plurality of sections, and means hingedly connecting the sections together.

4. A device for use in the manufacture of 100 confections comprising a plurality of sections, means hingedly connecting the sections together, and spring means normally urging the sections apart.

5. In a device for use in the manufacture 105 of confections the combination of a plurality of supporting sections, means connecting the sections for relative movement, means normally urging the sections away from each other, and means limiting the amplitude of movement of said sections away 110 from each other.

6. In a device for use in the manufacture 115 of confections the combination of a plurality of sections, means hingedly connecting the sections together, spring means normally urging the sections apart from each other, and means acting upon said sections to limit the amplitude of movement away from each other as caused by said spring means.

7. As an article of manufacture a confection supporting member comprising a body portion, a hook having a straight body portion and a pointed shank portion at right angles to the body portion, and means for non-movably connecting the body portion of the hook in the body portion of said article of manufacture.

8. As an article of manufacture a support 130 for confections comprising a substantially

- rectangular shaped body portion having sockets in the opposite sides thereof, a hook including a straight portion having a forward outturned pointed shank and a rearward inturned portion, and a retaining angle for connecting the straight portion of the hook to the rectangular body portion of said article of manufacture with the inturned end seated in the body portion to non-movably position the hook with the pointed shank in unimpeded outwardly extending relation from the body portion.
9. A device to facilitate the handling of confections comprising a plurality of sections for independently supporting articles of confection, and means pivotally connecting the sections so that they may be moved into abutting relation or expanded fan shaped relation.
10. A device to facilitate the handling of confections comprising a plurality of sections for independently supporting articles of confection, means pivotally connecting the sections so that they may be moved into abutting relation or expanded fan shaped relation, and spring means normally tending to urge the sections apart into fan shaped relation.
11. A device to facilitate the handling of confections comprising a plurality of sections for independently supporting articles of confection, means pivotally connecting the sections so that they may be moved into abutting relation or expanded fan shaped relation, spring means normally tending to urge the sections apart into fan shaped relation, and means connecting the sections together so that they may have a limited amplitude of movement away from each other.
12. A device of the class described comprising sections having sockets in opposite sides thereof, and springs in the sockets normally urging the sections apart.
13. In a device of the class described the combination of a plurality of sections including body portions and hook portions extending outwardly therefrom, means hingedly connecting the body portions remote from said hook portions, said body portions in the facing surfaces thereof having sockets, and springs compressed in said sockets normally urging the sections apart.
14. In a device of the class described the combination of a plurality of sections including body portions and hook portions extending outwardly therefrom, means hingedly connecting the body portions remote from said hook portions, said body portions in the facing surfaces thereof having sockets, springs compressed in said sockets normally urging the sections apart, and a chain connected to the body portions of said sections so that the sections may have a limited amplitude of movement away from each other.
15. A dipping device comprising a plurality of hingedly connected members adapted to be moved into close engagement with each other, spring means for forcing said members apart, and article receiving and supporting members carried by the hingedly connected members.
16. A dipping device comprising a plurality of hingedly connected members adapted to be moved into engagement with each other and spread apart, spring means for spreading said members apart, means for limiting the movement of the members during the spreading operation and article receiving members carried by the hingedly connected members.

OSCAR N. AMUNDSON.
